UNITED STATES PATENT OFFICE.

ELISIA R. BRANCH, OF WATERVILLE, MAINE.

DESIGN FOR A CLAMP FOR DOOR-SECURERS.

SPECIFICATION forming part of Design No. 28,565, dated May 10, 1898.

Application filed February 21, 1898. Serial No. 671,201. Term of patent 7 years.

To all whom it may concern:

Be it known that I, ELISHA R. BRANCH, a citizen of the United States, residing at Waterville, in the county of Kennebec and State 5 of Maine, have invented and produced a new and original Design for a Clamp for Door-Securers; and I do hereby declare the following to be a full, clear, and exact description of the same, reference being had to the accompanying drawing, forming a part thereof.

In the accompanying drawing the figure represents a perspective view illustrating my design for a clamp for a door-securer.

The leading and essential feature of my design consists of an outwardly-flaring yoke-like body portion having its ends turned outwardly at approximate right angles to said body portion and having a passage extending longitudinally through the looped end of said body portion.

The clamp as illustrated in the drawing

and embodying my design consists of an outwardly-flaring yoke-like body portion a , having flattened sides a' , and with its outer ends a^2 a^2 extended outwardly and approximately at right angles to its sides. The looped end of the body portion is somewhat rounded, as at a^3 , and is formed with a circular opening a^4 , extending longitudinally through the same. 30

Having now described my invention, what I claim as new, and desire to secure by Letters Patent, is—

The design for a clamp for a door-securer, substantially as herein shown and described. 35

In testimony whereof I hereunto affix my signature in presence of two witnesses.

ELISIA R. BRANCH.
